DOORSTOP

Louisa E. Hasselberger, East Hampton, N. Y.

Application July 30, 1932. Serial No. 626,981

2 Claims. (Cl. 292—344)

The invention aims to provide a new and advantageous stop for holding doors in open position, said stop being of such nature as to be hung upon the usual door knob so that it may be removed to allow swinging of the door, without the necessity of either stooping to lift the stop or sliding it upon the floor with the foot.

Another object is to provide a stop which may rest solidly upon the floor when removed from the knob, without danger of the upstanding handle by which it is lifted, falling from a readily accessible vertical position.

A still further object is to provide a stop which is simple and inexpensive and may therefore be manufactured and marketed at little expense, and consequently sold at small price.

With the foregoing in view, the invention resides in the novel subject matter hereinafter described and claimed, description being accomplished by reference to the accompanying drawing.

Fig. 1 is a perspective view showing the stop hung upon a door knob.

Fig. 2 is a perspective view illustrating the manner in which the stop may stand upon the floor.

Fig. 3 is an enlarged fragmentary rear elevation.

Fig. 4 is an enlarged fragmentary vertical section on line 4—4 of Fig. 3, but showing the upper and lower weight sections in the right angular relation illustrated in Fig. 2.

The construction shown will be specifically described, with the understanding however, that within the scope of the invention as claimed, numerous variations may be made, and in this connection, it may be stated that although the weight herein disclosed is shown of plain form, it may in practice be of any desired shape, for instance, to simulate a frog.

The above mentioned weight comprises upper and lower sections 5 and 6 hinged together on a horizontal axis, and in the present showing, the section 5 is provided with two downwardly projecting hinge knuckles 7 between which a relatively large hinge knuckle 8 on the section 6, is received, a pintle 9 being passed through said knuckles. Suitable springs 10 are mounted on the pintle 9 within recesses 11 in the back of the knuckle 8, the ends of said springs being seated in recesses 12 in the weight sections 5 and 6. These springs 10, hold the upper weight section 5 in a perpendicular position as seen in Figs. 2 and 4, when the lower section 6 is allowed to rest horizontally upon the floor, the flat rear side

of said section 6 then forming a stable supporting surface.

A vertically elongated handle 13 is secured at its lower end to the upper weight section 5, the upper end of said handle being shaped to hang upon a conventional door knob 14, so that said handle 13 and said upper weight section 5 form suspending means for the lower weight section 6, the latter section being adapted to contact with the floor in an inclined position when the handle 13 is engaged with the knob, as seen in Fig. 1. The weight of this section 6 is such that the springs 10 cannot swing it upwardly from contact with the floor and hence the door will be effectively held against accidentally closing. When the device is hung upon a comparatively high door knob, the weight 6 will stand almost vertically, as shown in Fig. 1, but when hung upon a relatively low knob, said weight section 6 will be less steeply inclined, said weight section being self-adjusted to the proper position, due to its hinged connection with the upper section 5.

Whenever the door is to be moved, the handle 13 may be readily grasped without stooping, and the entire device easily lifted from engagement with the door knob. When so lifted, the weight section 6 will hang vertically by gravity, but when the lower end of this weight section is allowed to touch the floor and the remainder of the device is then lowered, the hinge will come into play allowing the section 6 to rest horizontally upon the floor while the section 5 and the handle 13 are disposed vertically as seen in Fig. 2. The springs 10 then function to hold the parts 5 and 13 in upright position, so that the device may again be readily lifted without stooping when it is to be returned to its normal position and hung upon the knob. If desired, the device could of course be merely placed against the door with the parts in the relation shown in Fig. 2, without hanging the handle upon the door knob, but it is preferable to hang the stop upon the knob so that the door will be held against movement in both directions.

I claim:—

1. A door stop comprising a weight formed of upper and lower sections hinged together on a horizontal axis, the lower section being adapted to contact with the floor in an inclined position or to rest solidly on the floor in a horizontal position, a vertically elongated handle secured at its lower end to said upper section, the upper end of said handle being adapted for hanging upon a door knob to suspend the stop with said lower section in said inclined position, and spring means

100

105

110

for holding said upper section and handle upright when said lower section rests horizontally on the floor.

2. A door stop comprising a weight formed of 5 upper and lower sections hinged together on a horizontal axis, the lower section being adapted to contact with the floor in an inclined position or to rest solidly on the floor in a horizontal position, and a vertically elongated handle secured

at its lower end to said upper section, the upper end of said handle being adapted for hanging upon a door knob to suspend the stop with said lower section in said inclined position, said upper section and handle being adapted for upright positioning when said lower section rests horizontally on the floor.

LOUISA E. HASSELBERGER.
